UNITED STATES PATENT OFFICE

JOHN Z. EARLEY, OF MIAMI, FLORIDA

ELECTRIC SIGN

Application filed June 4, 1932. Serial No. 615,388.

My invention relates to improvements in electric signs of the type in which conductive gas is caused to glow by the passage of an electric discharge, and it consists in the combinations, constructions and arrangements herein described and claimed, and in the process of making the sign.

In the ordinary sign of the type, that is, those signs in which tubes that contain conductive gases are used, it is necessary to have strong tubing, and to space this tubing from the support to satisfy insulation requirements. It is also ordinary to pass the tube through openings or holes in the support, and these holes are unsightly. A sign made this way is quite fragile.

An object of my invention is to provide an electric sign of the type mentioned in which the tubing is supported in such a manner as to eliminate the danger of breaking the tube.

A further object is to provide an insulating support for the tube which obviates the necessity of clamping devices, posts, tie-wires, etc.

A further object is to provide a sign, making use of a tube of this type, in which characters are formed, the elements of the characters being exposed, and all connections cross-overs, double-backs, etc., being concealed in plastic material.

A further object is to provide a process by means of which a sign of this type may be made at comparatively little expense, the sign being capable of being handled or shipped with little liability of breaking.

Other objects and advantages will appear in the following specification, and the novel features of the invention will be particularly pointed out in the appended claims.

My invention is illustrated in the accompanying drawing forming part of this application, in which:

Figure 1 is a face view of a sign constructed in accordance with my invention, and,

Figure 2 is a section on the line 2—2 of Fig. 1.

In carrying out my invention I make use of a transparent tube, such as a glass tube,

which is intended to contain the conducting gas. This tube is bent by a glass blower over an asbestos pattern, for instance in the form of the word "Turn". The conducting gas is introduced and the tube sealed. It is then dipped two or three times in melted paraffine or bees wax. The object of this treatment is to provide a soft buffer coat between the glass and the embedding material in which it is to be cast.

The word formed from the glass is now laid down on a piece of plate glass and a suitable 24 gauge galvanized iron frame of proper size and about $\frac{3}{4}$ inches deep is placed around it. Plaster of Paris is poured in and current from a suitable transformer is passed through the tubing while the plaster sets up. This current warms the tubing and softens the wax somewhat which takes up the difference in expansion and contraction of the two materials, i. e., the glass and the plaster. While the plaster is drying from time to time current is passed through the tube to soften the wax, thus equalizing any strains that may develop.

When the plaster is set, the tubing is lighted and, as the glass is very near the surface, the design can be easily seen and outlined on the surface with a pencil. Later the plaster is tooled away in some form of bevel from those parts of glass intended to be active, that is, those parts which will show in the finished sign.

In the drawing the various elements which are visible, that is to say, the letters in the present instance, are indicated at 3. The connecting portions of the tube, which in the present instance are behind the plane of the visible portions, are indicated at 4. Certain portions of the tube are doubled back upon themselves as shown at 5. The embedding plastic material 6 may be reinforced by wire, as shown at 7, and the ends of the tube are brought out to terminals 8, which are also embedded in the plastic material, and to which conductors 9 are connected. As will be seen from the drawing, the elements are disposed in channels formed by the cut-away portions 11. This obviates the necessity of making channels or troughs

of metal, such as are often seen with tubes of this type. By casting the plastic material around the tube and cutting the channels a number of advantages are secured. 5 The tube is held by the plastic material at all portions except at the front exposed sides of the elements. The glass tubing, therefore, does not have to be as thick or as strong as in the ordinary construction. The intervening connections are completely concealed, thus doing away with blackening these portions.

10 There are no openings in the sign face to render the latter unsightly and the channels form recesses which are illuminated and which tend to give the effect of a wider element, without the necessity, however, of going to the trouble of providing separate compartments, or channels of metal or other 20 material.

15 While the invention relates primarily to electric signs, it is obvious that it could be used in the formation of borders, designs, displays or patterns, without departing from 25 the spirit of the invention. Any suitable plastic material might be used in lieu of the plaster of Paris mentioned.

I claim:

20 1. An electric sign of the type described comprising a transparent tube having visible portions disposed in a common plane, and connecting portions behind said plane, a plastic coating for said tube and a hardened plastic support embedding the 35 plastic-coated tube, said plastic coating serving as a cushioning means for preventing any fracture of the tube due to the differ-

ence in expansion and contraction between the tube and support.

2. An electric sign of the type described 70 comprising a glass tube having visible portions disposed in a common plane, and connecting portions behind said plane, a fusible wax coating for said tube and a hardened plastic support imbedding the wax-coated tube, said wax coating serving as a cushioning means for preventing any fracture of 15 the tube due to the difference in expansion and contraction between the tube and the support.

3. The herein described process of making 80 electric signs which consists in forming elements of characters in a common plane from certain portions of a glass tube, bending the connecting portions to the rear of said plane, coating the tube with a fusible wax, embedding the coated tube in plastic material and maintaining the wax coating 85 in a plastic condition during the hardening of the plastic material.

4. The herein described process of making 90 electric signs which consists in forming elements of characters in a common plane from certain portions of a glass tube, bending the connecting portions to the rear of said plane, coating the tube with a fusible wax, embedding the coated tube in plastic material and maintaining the wax coating 95 in a plastic condition during the hardening of the plastic material and subsequently cutting away the plastic material and the wax coating to expose one side of the elements.

JOHN Z. EARLEY.
